UNITED STATES PATENT OFFICE.

CHARLES G. MAHANA, EARL D. GLIDDEN, AND MILTON P. LAURENT, OF THREE RIVERS, MICHIGAN, ASSIGNORS TO FAIRBANKS MORSE & COMPANY, OF CHICAGO, ILLINOIS, A CORPORATION.

RAILWAY MOTOR-CAR.

1,346,227.

Specification of Letters Patent. Patented July 13, 1920.

Application filed April 26, 1920. Serial No. 376,636.

To all whom it may concern:

Be it known that we, CHARLES G. MAHANA, EARL D. GLIDDEN, and MILTON P. LAURENT, citizens of the United States, residing at 5 Three Rivers, county of St. Joseph, State of Michigan, have invented certain new and useful Improvements in Railway Motor-Cars, of which the following is a specification.

This invention relates to improvements in 10 railway motor cars.

The main object of this invention is to provide an improved railway motor car which is light in weight so as to permit its being handled by one man in placing on or 15 removing from the track and at the same time is not likely to leave the track when in use.

A further object is to provide an improved railway motor car having these advantages 20 which is quite simple and economical in structure and very durable in use.

Further objects, and objects relating to structural details, will definitely appear from the detailed description to follow.

25 We accomplish the objects of our invention by the devices and means described in the following specification. The invention is clearly defined and pointed out in the claims.

30 A structure which is a preferred embodiment of our invention is clearly illustrated in the accompanying drawing forming a part of this specification, in which:

Figure I is a plan view of a railway motor car embodying the features of our invention, certain parts being shown conventionally for convenience in illustration.

Fig. II is a rear elevation.

Fig. III is a detail view partially in transverse section on a broken line corresponding to line 3—3 of Fig. V, showing details of the engine mounting.

Fig. IV is a detail section on a line corresponding to line 4—4 of Fig. II showing details of one of the axle supporting bearings.

Fig. V is an inverted view of the engine supporting saddle.

In the drawing similar reference characters refer to similar parts throughout 50 several views and the sectional views are taken looking in the direction of the little arrows at the ends of the section lines.

Referring to the drawing, we provide a frame comprising a front sill or cross mem-

ber 1, and rear sill or cross member 2. These 55 are connected at one side by the longitudinal side member 3 and at the other side by a pair of longitudinal sills 4. The longitudinal sills 4 are extended beyond the cross members to provide handles 5. The connections for 60 these cross members and longitudinal members are indicated conventionally.

We preferably provide a diagonally disposed brace 6 secured at its front end to the front cross member at 7 adjacent to the inner of the pair of longitudinal sills 4. The rear end of this brace is secured to the rear cross member at 8 adjacent the rear end of the side member.

A narrow deck 9 is secured to the cross 70 members and constitutes a frame member, the tool box 10 being provided on this deck and also a box 11 to receive tools or the like.

The seat, in the structure illustrated, consists of uprights 12 mounted on the longitudinal sills 4 and having a flat top 13 provided with end rails 14. With the parts thus arranged we secure a light and very rigid frame.

The spindles 15 for the front wheels 16 80 are mounted on the ends of the front cross member 1.

The axle 17, for the rear wheels 18, is a live axle and is supported at its ends in bearings 19 on the hangers 20.

It will be noted that the seat is well to one side, but being between the wheels the weight does not tend to overbalance the car as is the case where the seat is directly over the two wheels on one side of the car as is 90 the case in nearly all motor cars of this general type.

The engines 21 are shown mainly conventionally, and are provided with crank cases 22 having opposed inwardly projecting bearings 23 for the crank shaft 24 which, in the structure illustrated, is common to both engines. The engines are mounted on the saddle 25 secured on the under sides of the longitudinal sills 4, the saddle extending from 100 sill to sill and constituting means for supporting the engines in a fixed or positive relation to each other.

The crank shaft 24 is provided with a gear 26 which meshes with the gear 27 on 105 the axle 17. To prevent the springing of the axle and to hold the gears in proper meshing relation we provide a bearing 28

secured to the rear end of the crank casing of the inner engine by means of the screws 29. Shims 30 may be provided between the bearing and crank casing for adjusting the bearing to the axle.

With this arrangement of parts, we provide a railway motor car which may be run at high speeds without danger of leaving the track and at the same time one which is 10 light in weight and may be easily managed to place upon or remove from the track by a single operator.

Having thus described our invention, what we claim as new and desire to secure by Letters Patent, is:

1. In a railway motor car, the combination of a frame comprising front and rear cross members, a longitudinal side member connecting said cross members at one side, a 20 pair of spaced longitudinal sills connecting said cross members at the other side, spindles mounted on said front cross member, hangers provided with axle bearings mounted at the ends of the rear cross members, a 25 live axle mounted in said hanger bearings, wheels on said axle and spindles disposed at the outer side of said longitudinal frame members, an engine supporting saddle secured on the under side of said sills, a pair 30 of internal combustion engines mounted horizontally on said saddle and provided with crank cases having opposed inwardly projecting crank shaft bearings, a supporting bearing for said axle mounted on the 35 rear end of the crank case of the inner engine, a crank shaft common to both engines, and meshing gears on said crank shaft and axle.

2. In a railway motor car, the combination 40 of a frame comprising front and rear cross members, a longitudinal side member connecting said cross members at one side, a pair of spaced longitudinal sills connecting said cross members at the other side, spindles mounted on said front cross member, hangers provided with axle bearings mounted 45 at the ends of the rear cross member, a live axle mounted in said hanger bearings, wheels on said axle and spindles disposed at the outer side of said longitudinal frame members, an engine supporting saddle secured 50 on the under side of said sills, an internal combustion engine mounted horizontally on said saddle, and driving connections 55 for said engine to said axle.

3. In a railway motor car, the combination 60 of a frame comprising front and rear cross members, a longitudinal side member connecting said cross members at one side, a pair of spaced longitudinal sills connecting said cross members at the other side and extending beyond them to provide handles, a 65 diagonally disposed brace secured at its front end to the front cross member adjacent the inner of the said pair of longitudinal

sills and at its rear end to the rear cross member adjacent the rear end of said side member, a seat comprising uprights mounted on said sills and a top on said uprights, a narrow deck mounted on said cross members 70 at the inner side of said seat and constituting a frame member, spindles mounted on said front cross member, hangers provided with axle bearings mounted at the ends of the rear cross member, a live axle mounted 75 in said hanger bearings, wheels on said axle and spindles disposed at the outer side of said longitudinal frame members, an engine supporting saddle secured on the under side of said sills, an internal combustion engine 80 mounted horizontally on said saddle and driving connections for said engine to said axle.

4. In a railway motor car, the combination 85 of a frame comprising front and rear cross members, a longitudinal side member connecting said cross members at one side, a pair of spaced longitudinal sills connecting said cross members at the other side and extending beyond them to provide handles, 90 a diagonally disposed brace secured at its front end to the front cross member adjacent the inner of the said pair of longitudinal sills and at its rear end to the rear cross member adjacent the rear end of said 95 side member, a seat comprising uprights mounted on said sills and a top on said uprights, a narrow deck mounted on said cross members at the inner side of said seat and constituting a frame member, spindles 100 mounted on said front cross member, hangers provided with axle bearings mounted at the ends of the rear cross member, a live axle mounted in said hanger bearings, wheels on said axle and spindles, the wheels at one 105 side being disposed at the outer side of said longitudinal frame members, and an engine mounted on said sills.

5. In a railway motor car, the combination 110 of a frame comprising front and rear cross members, a longitudinal side member connecting said cross members at one side, a pair of spaced longitudinal sills connecting said cross members at the other side, spindles on said front cross member, axle bearings at the ends of the rear cross member, a live axle mounted in said bearings, wheels on said axle and spindles disposed at the outer side of said longitudinal frame members, an engine supporting saddle secured 115 on the under side of said sills, a pair of internal combustion engines mounted horizontally on said saddle, a supporting bearing for said axle mounted on one of the engines, a crank shaft common to both 120 engines, and meshing gears on said crank shaft and axle.

6. In a railway motor car, the combination 125 of a frame comprising front and rear cross members, a longitudinal side member 130

connecting said cross members at one side, a pair of spaced longitudinal sills connecting said cross members at the other side, spindles on said front cross member, axle bearings 5 on the rear cross member, a live axle mounted in said bearings, wheels on said axle and spindles disposed at the outer side of said longitudinal frame members, an engine supporting saddle secured on the under side 10 of said sills, a pair of internal combustion engines mounted horizontally on said saddle, and driving connections for said engines to said axle.

7. In a railway motor car, the combination 15 of a frame comprising front and rear cross members, a longitudinal side member connecting said cross members at one side, a pair of spaced longitudinal sills connecting said cross members at the other side, 20 spindles on said front cross member, axle bearings at the ends of the rear cross member, a live axle mounted in said bearings, wheels on said axle and spindles disposed at the outer side of said longitudinal frame 25 members, an engine supporting saddle secured on the under side of said sills, an internal combustion engine mounted on said saddle, a supporting bearing for said axle mounted on said engine, and driving connections 30 for said engine to said axle.

8. In a railway motor car, the combination 35 of a frame comprising front and rear cross members, a longitudinal side member connecting said cross members at one side, a pair of spaced longitudinal sills connecting said cross members at the other side, a seat mounted on said sills, a deck mounted on said cross members at the inner side of said seat, spindles on said front cross member, 40 axle bearings at the ends of the rear cross member, a live axle mounted in said bearings, wheels on said axle and spindles disposed at the outer side of said longitudinal frame members, an engine mounted on 45 said sills, a bearing for said axle mounted on said engine, and driving connections for said engine to said axle.

9. In a railway motor car, the combination 50 of a frame comprising front and rear cross members, a longitudinal side member connecting said cross members at one side, a pair of spaced longitudinal sills connecting said cross members at the other side, spindles on said front cross member, axle 55 bearings at the ends of the rear cross member, a live axle mounted in said bearings, wheels on said axle and spindles disposed at the outer side of said longitudinal frame members, an engine mounted on said sills, 60 a bearing for said axle mounted on said engine, and driving connections for said engine to said axle.

10. In a railway motor car, the combination 65 of a frame comprising a rear cross member, a pair of spaced longitudinal sills, axle bearings on the rear cross member, a live axle mounted in said bearings, traction wheels on said axle, an engine supporting saddle secured on the under side of said sills, a pair of internal combustion engines 70 mounted horizontally on said saddle and provided with crank cases having opposed inwardly projecting crank shaft bearings, a supporting bearing for said axle mounted on the rear end of one of the crank cases, 75 a crank shaft common to both engines, and meshing gears on said crank shaft and axle.

11. In a railway motor car, the combination 80 of a frame comprising a rear cross member, a pair of spaced longitudinal sills, axle bearings on the rear cross member, a live axle mounted in said bearings, traction wheels on said axle, an engine supporting saddle secured on the under side of said sills, a pair of internal combustion engines 85 mounted horizontally on said saddle and provided with crank cases having opposed inwardly projecting crank shaft bearings, a crank shaft common to both engines, and driving connections for said crank shaft and 90 axle.

12. In a railway motor car, the combination 95 of a frame comprising a rear cross member, a pair of spaced longitudinal sills, axle bearings on the rear cross member, a live axle mounted in said bearings, traction wheels on said axle, an engine supporting saddle secured on the under side of said sills, a pair of internal combustion engines mounted on said saddle, a supporting bearing for said axle mounted on one of the engines, and driving connections for said engines and axle.

13. In a railway motor car, the combination 105 of a frame comprising a rear cross member, a pair of spaced longitudinal sills, axle bearings on the rear cross member, a live axle mounted in said bearings, traction wheels on said axle, an engine supporting saddle secured on the under side of said sills, an internal combustion engine mounted on said saddle, a supporting bearing for said axle mounted on said engine, and driving connections for said engine and axle.

In witness whereof we have hereunto set 110 our hands and seals in the presence of two witnesses.
